UNITED STATES PATENT OFFICE

159,974

GREETING CARD WITH COMPARTMENTS
FOR THE INSERTION OF PANELS

Maurice F. Garrett, Manhasset, N. Y.

Application March 10, 1950, Serial No. 8,451

Term of patent 3½ years

(Cl. D59—13)

To all whom it may concern:

Be it known that I, Maurice F. Garrett, a citizen of the United States of America, residing in Manhasset, county of Nassau, and State of New York, have invented a new, original, and ornamental Design for a Greeting Card with Compartments for the Insertion of Panels, of which the following is a specification, reference being had to the accompanying drawing, forming part thereof, wherein

Figure 1 is a front elevational view of a greeting card with compartments for the insertion of panels, showing my new design with panels inserted in the compartments;

Figure 2 is a side elevational view thereof; and

Figure 3 is a front elevational view showing the panels separated from the compartments.

The rear of the greeting card is substantially plain in appearance.

The characteristic features of my design reside in the portions shown in full lines in the drawing.

I claim:

The ornamental design for a greeting card with compartments for the insertion of panels, substantially as shown and described.

MAURICE F. GARRETT.
